CONTAINER CONSTRUCTION

Maximilian P. Link, Los Angeles, Calif.

Application February 5, 1938, Serial No. 188,901

6 Claims. (Cl. 229—5.7)

This invention relates to containers and relates more particularly to containers formed of paper or fibrous materials. A general object of this invention is to provide a simple, effective and attractive closure construction for containers of the character referred to.

Another object of this invention is to provide an improved head or closure for a container of fibrous material that embodies an inner seal or head proper of fibrous material, an outer seal or disc that may be domed, convexed or given any other ornamental configuration and a single metal seam securing the outer disc to the head proper and that may serve to seam the entire closure to the wall or body of the container.

Another object of this invention is to provide a container construction of the character mentioned in which the metal seam ring is shaped, prior to its assembly on the head proper, to securely and dependably retain the outer member or disc in place.

Another object of this invention is to provide a container construction of the character mentioned embodying novel and inexpensive means for maintaining the outer disc in spaced relation to the head proper to give the closure additional thickness and to make it more symmetrical.

Another object of this invention is to provide a container construction of the character mentioned in which the seam ring may be flush or substantially flush with the outer surface of the outer disc and does not have any sharp edges or corners.

Another object of this invention is to provide a container construction of the character mentioned in which adhesive is not employed and in which it is not necessary to employ a spacer, pad or additional material to maintain the outer disc in the desired spaced relation to the head proper.

Another object of this invention is to provide a container closure of the character referred to that may be frictionally engaged on the container to form a removable cover or that may be securely seamed to the container to form a fluid-tight closure.

Another object of the invention is to provide a container closure of the character mentioned that is of minimum bulk and that will remain rigid and in correct frictional cooperation with the container when subject to atmospheric and temperature changes.

Another object of the invention is to provide a container closure that does not have any metal parts in contact with the contents of the con-

tainer and that does not at any time present any raw edges.

A further object of this invention is to provide a container construction of the character mentioned in which the closure is easy to manufacture and assemble and may be readily applied to or seamed to the container at the time of packaging or filling the same.

The various objects and features of my invention will be fully understood from the following detailed description of typical preferred forms and applications of my invention, throughout which description reference is made to the accompanying drawing, in which:

Fig. 1 is a side elevation of a container embodying one form of closure means of the invention. Fig. 2 is an enlarged fragmentary vertical detailed sectional view of the container illustrated in Fig. 1. Fig. 3 is an enlarged fragmentary vertical detailed sectional view illustrating the seam construction of the top or upper closure of the container. Fig. 4 is a view similar to Fig. 3 illustrating the seam of the lower closure of the container. Fig. 5 is a view similar to Fig. 3 illustrating a slightly modified form of the construction shown in that figure. Fig. 6 is a vertical detailed sectional view of the upper closure of a container embodying another form of the invention. Fig. 7 is a view similar to Fig. 6, showing still another form of the invention. Fig. 8 is an enlarged fragmentary vertical detailed sectional view of the seam means of the structure shown in Fig. 6 and Fig. 9 is an enlarged fragmentary vertical detailed sectional view of the seam means of the structure shown in Fig. 7.

While the construction of the present invention may be adapted for various applications it is particularly suited for embodiment in paper containers or containers of fibrous material. The invention may be embodied in containers for holding cosmetics, food stuffs, liquids, pastes, powders and many other products and may be embodied in containers of various shapes and proportions.

The container construction of the present invention illustrated in Figs. 1 to 4, inclusive, of the drawing, comprises, generally, a container body 10 having a bottom closure 11, and a top closure for the body 10 including a sealing head 12, and an outer head or disc 13, a spacer 14 for holding the disc 13 in spaced relation to the head 12 and a metal seam ring 15 securing the disc 13 to the head 12 and adapted to seam the closure to the container body 10.

The container body 10 is preferably tubular

and in accordance with the invention may comprise a length of tubular fibrous material such as paper, pressed paper, cardboard, or the like. For example, the body 10 may be formed of a length of tubing made from a spirally wound strip of material of the class just referred to. I have illustrated the body 10 as being cylindrical, although it is apparent that it may be tapered, polygonal or any other desired shape. The body 10 may be treated or coated either internally or externally, or both, to make it water-tight or resistant to the material which the container is intended to hold.

The bottom or lower closure 11 may be fixed or seamed to the body 10 before the container is supplied to the packager. However, when a frangible closure or seal is provided for the container to be within or under the top closure, as described and claimed in my copending application Serial No. 64,081, the bottom closure 11 may be only partially seamed to the body 10 when the container is supplied to the packager so that it may be easily removed to permit filling of the container and then replaced for final seaming to the container body. The closure 11 includes a disc-like head 16 of paper, pressed paper, cardboard, or similar fibrous material. The head 16 may be treated or coated to resist the action of the material for which the container is intended. The major portion of the head 16 may be flat as illustrated, although it is obvious that the head may be embossed or corrugated if desired. The peripheral portion of the head 16 is shaped for cooperation with the body 10. An axial flange 17 is provided on the head 16 and is adapted to fit in the lower portion of the body 10. The flange 17 is annular and is preferably flared to tightly seat or engage against the internal surface 18 of the tubular body 10. The head 16 further includes a rim 19 projecting outwardly or radially from the flange 17. As initially formed the rim 19 projects horizontally or laterally from the lower end of the flange 17 and is flat. The lateral flange 19 engages upwardly against the lower end of the body 10. When the head 11 is seamed to the body 10 the rim 19 has a portion 20 bent or turned upwardly at the exterior of the body. The flange 17 and the rim 19 are gripped or engaged by a metal seam ring 21.

The seam ring 21 is a continuous substantially cylindrical member arranged within the flange 17 to bear outwardly against the same. A radially or laterally projecting flange 22 is provided on the ring 21 and bears upwardly against the lower surface of the rim 19. As initially formed the flange 22 is flat and substantially horizontal and when seamed the flange 22 is provided with a lip 23 that extends upwardly or axially to engage against the outer surface of the portion 20 and that is curled or wrapped about the edge of the portion 20 to have a part 24 that grips against the external surface of the container body 10 and that grips the internal surface of the portion 20. It will be seen that the curled-under part 24 tightly gripping the external surface of the body 10 holds the fibrous flange 17 in tight sealing engagement with the internal surface 18 of the body, holds the rim 19 against the end surface of the body 10 and securely retains the closure 11 on the container. The seam construction or closure construction just described forms the subject of my copending application, Serial No. 48,846, filed November 8, 1935.

The top closure for the container 10 is a feature of the invention. In accordance with the inven-

tion this top closure is such that it may be tightly seamed to the body 10 to form an effective air and fluid-tight seal or may be rather loosely seamed to the body 10 or merely frictionally engaged on the body 10 to be readily removable by hand and in any case to be replaceable to form a convenient cover for the container. Further, the top closure of the container 10 is formed and shaped to give the container a pleasing appearance and to clearly indicate to the user that it is the top closure or cover of the container.

The sealing head 12 of the top closure may be similar to or identical with the above described head 16 of the bottom closure 11. The head 12 is a disc shaped member that may be formed of paper, pressed paper, cardboard, or other fibrous materials. If desired or necessary the head 12 may be coated, treated or lined to be fluid-tight or resistant to the material held in the container 10. The major portion of the head 12 may be flat as illustrated, although if desired, the head may be corrugated or embossed. The peripheral portion of the head 12 is shaped to cooperate with the upper end part of the body 10. An upwardly or outwardly projecting annular flange 25 is provided on the head 12 and is adapted to cooperate with the internal surface 18 of the body 10. The flange 25 is preferably flared upwardly and outwardly to tightly or frictionally seal with the internal body surface 18. The head 12 is further provided with a laterally or outwardly projecting rim 26. The rim 26 is annular or continuous and integrally joins the outer end of the flange 25. As initially formed the rim 26 is flat and substantially normal to the rim 25 and is proportioned to project outwardly beyond the external surface of the body 10. The lower side of the rim 26 is adapted to rest downwardly against the upper end of the body 10. It will be observed that both the flange 25 and the rim 26 have direct cooperation or engagement with surfaces of the fibrous container body 10. As the container body 10 and the head 12 are both formed of fibrous material, this cooperation assures an effective seal and a desirable frictional engagement in the case where the closure forms a removable and replaceable cover.

The outer head or disc 13 is provided to increase the thickness of the cover or top closure, to add to the strength of the closure, to protect a frangible inner seal (not shown) when such a seal is employed, and to give the closure a pleasing appearance. The disc 13 may also serve to carry a label or suitable ornamentation and to provide a substantially flush upper surface for the container. In practice the disc 13 may be formed of any suitable material, for example, it may be formed of sheet metal, cardboard, paper, pressed paper, or any other suitable material. In the present disclosure the disc 13 may be considered as formed of fibrous material. The disc 13 is proportioned so that its periphery is spaced inwardly from the internal surface of the head flange 25. The disc 13 may be given any desired ornamental configuration. In the typical case illustrated the disc 13 is domed or shaped to present a smooth convex external surface and a smooth concave inner surface. It is to be understood that the disc 13 may be other shapes, for example, it may have graduated annular terraces and steps, corrugations or embossing of various kinds, etc., or it may present a concave upper surface. The disc 13 overlies the head 12 and is preferably in spaced relation to the head.

The spacer 14 is provided to support or main-

tain the disc 13 in the desired spaced relation to the head 12. The spacer 14 may be varied in character without departing from the invention. The spacer 14 may be a washer-like ring of solid cardboard, felt or the like or may be a double or single faced corrugated board ring as illustrated. The spacer 14 lies against the upper surface of the head 12 and has its periphery in spaced adjacent relation to the flange 25. The peripheral portion of the disc 13 is adapted to rest against the upper surface of the spacer 14. The spacer 14 may be adhesively secured to the head 12 or the disc 13 or both. This is not necessary, however, as the seam ring 15 holds the several parts 5 of the closure assembly in the proper relation without resorting to the use of adhesive.

The seam ring 15 serves to hold the several parts of the top closure together to form a unitary structure, to hold the flange 25 in shape to frictionally engage and seal with the internal surface 18 of the body 10, to support the rim 26 for engaging against the end of the body 10 and if desired, may be employed to either tightly or loosely seam or secure the closure to the body 10, 25 in which case it serves to grip or frictionally engage the exterior of the body 10.

In accordance with the invention the ring 15 is a continuous one-piece annular member of sheet metal of suitable gauge. The ring 15 may be plated, painted or otherwise finished to have the desired appearance. In accordance with the invention, the ring 15 has a substantially cylindrical inner part 28 that engages or bears outwardly against the internal surface of the flange 25. The ring part 28 is tubular or extends axially with relation to the longitudinal axis of the container body 10 and has its inner edge or end resting against the upper surface of the head 12. The ring part 28 is of sufficient extent or length to extend outwardly to or adjacent the outer surface of the spacer 14. The periphery of the spacer 14 preferably cooperates with the ring part 28 and this cooperation holds the spacer 14 centralized.

It is an important feature of the invention that the seam ring 15 cooperates with the disc 13 to hold the same against outward movement and displacement. The ring 15 is provided with what I will term an inturned flange 29. The flange 29 is an integral part of the ring 15 and is formed by bending or crimping the metal of the ring. The in-turned flange 29 occurs at the upper end of the above described part 28 and projects inwardly therefrom relative to the central axis of the container body 10. The flange 29 is continuous or annular and overhangs and engages against the peripheral portion of the disc 13. The under side of the flange 29 engages downwardly against the disc 13 and being annular, has engagement with the disc throughout its circumference.

In the particular arrangement illustrated in the drawing the flange 29 slopes upwardly and inwardly to cooperate with the upper peripheral corner of the disc 13. The invention is not to be construed as limited to this particular arrangement as the angle or slope of the flange 29 may be varied to suit different conditions, for example, the flange 29 may be substantially horizontal to engage downwardly against the upper side of the disc 13 or may be pitched at a sharp angle to lie substantially flush with the upper surface of the disc. It is to be understood that the angle or pitch of the flange 29 may depend upon the configuration of the disc 13 or upon the posi-

tion of the peripheral portion of the disc 13. In any event the flange 29 is shaped or arranged to have retaining engagement with the disc 13. The flange 29 engaging downwardly against the peripheral portion of the disc 13 throughout its circumference holds the disc 13 downwardly against the spacer 14 to positively prevent outward displacement of the disc and to hold the disc against lateral shifting. The flange 29 preferably overlaps or overlies a substantial portion of the disc 13 to dependably retain the disc in place and prevent loss of the disc in the event of shrinkage, warping or distortion of the disc. If desired for any reason whatsoever, the flange 29 and the spacer 14 may be related so that the disc 13 may be turned with respect to the ring 15 and the head 12.

The ring 15 further includes an outwardly or laterally projecting flange or rim 30. The rim 30 extends outwardly from the upper end of the flange 29 and is an integral part of the ring 15. In the construction illustrated the rim 30 is substantially flat, it being understood that the rim 30 or a portion of the same may be curved or made convex or given any other configuration as desired. The rim 30 engages inwardly or downwardly against the upper side of the rim 26. As initially formed the rim 30 is generally flat and of sufficient width to extend outwardly beyond the periphery of the fibrous rim 26. When the ring 25 is seamed to the head 12 the projecting peripheral portion of the rim 30 is curled under to wrap or engage about the edge portion of the rim 26 and to cooperate with the under side of the rim 26. Fig. 3 of the drawing best illustrates the curled-under peripheral part 27 of the rim 30 curled about the edge of the rim 26. The curled-under part 27 provides the top closure with a smooth round metal peripheral surface that may be engaged or grasped for the purpose of removing and replacing the closure. The rim 30, shaped as just described to have the turned-under part 27, prevents fraying of the rim 26, strengthens the rim 26 and holds the rim in place for engagement with the upper end of the container body 10. The major portion of the rim 30 maybe sloped or made slightly convex to conform generally to the slope or shape of the domed disc 13 so that the upper surface of the closure assembly presents a smooth substantially flush appearance.

The rim 30 may be seamed or curled to have its part 27 grip inwardly against the external surface of the body 10 to secure or seam the top closure to the container. By referring to Fig. 4 it will be seen that the part 24 corresponds in location to the part 27 and it will be understood how the part 27 may be curled or seamed to grip the wall of the container body 10 tightly. The engagement of the part 27 with the container body 10 may be tight or firm or may be such that the top closure may be manually removed from the container without the employment of an opening device. If the top closure is intended to form a readily removable cover the rim 30 and the part 27 may be left as illustrated in Fig. 3 of the drawing so that the closure is held on the container through the frictional engagement of the flange 25 with the internal surface 18 of the body 10, and the frictional engagement of the part 27 with the external surface of the body 10. With the rim 30 and the part 27 shaped as illustrated in the drawing the peripheral portion of rim including the part 27 forms a conveniently engageable portion of the top closure that may

be grasped or engaged when removing and replacing the closure.

It is believed that the features of the form of the invention illustrated in Figs. 1 to 4 inclusive, of the drawing, will be readily apparent from the foregoing detailed description. It will be observed that the single metal ring 15 serves to dependably retain the disc 13 in place, maintain the flange 25 in condition for frictional engagement with the internal surface 18 of the body 10, covers and strengthens the rim 26 for cooperation with the end of the body 10, frictionally engages the external surface of the body to either loosely or securely seam the closure to the body and forms a smooth rounded periphery for the closure construction and the ring part 28 serves to re-inforce and back-up the fibrous flange 25 and to definitely locate the spacer 14. It will be observed that the ring part 28 and the rim part 27 are related so that the fibrous flange 25 and the body wall are frictionally gripped between them and therefore the flange 25 is removably retained in effective sealing cooperation with the internal surface 18 of the body 10. The flange 29 holds the disc 13 against outward displacement and maintains the disc in firm engagement with the spacer 14. The flange 29 overlaps the peripheral part of the disc 13 to conceal its edge and to provide the assembly with a smooth substantially continuous outer surface. The rim 30 with its turned-under part 27 substantially conceals the fibrous rim 26, braces and supports the rim 26, provides the rim 26 with a metal peripheral covering and either loosely or tightly engages the external surface of the container body 10 to loosely or tightly secure the closure to the body by the engagement of the flange 25 with the interior of the body and the frictional and gripping engagement of the part 27 with the exterior of the body 10.

Fig. 5 of the drawing illustrates a slight variation in the form of closure construction illustrated in Figs. 1 to 4, inclusive. In the construction shown in Fig. 5 the head 12, the disc 13 and the seam ring 15 may be the same as in the foregoing figures. The spacer 14 is eliminated and the inner part 28 of the ring 15 is crimped or distorted to have inwardly projecting lugs 31 cooperating with the under side of the disc 13 to hold the disc in spaced relation to the head 12. The lugs 31 are circumferentially spaced about the part 28 to cooperate with the under surface of the disc 13 at a number of points. In this construction the ring 15 serves to hold the disc against both inward and outward movement.

Figs. 6 and 8 of the drawing illustrate a form of container construction embodying the body 10, the head 12 and the seam ring 15, all described above, and an outer disc 13^a having means for holding itself in spaced relation to the head 12.

The disc 13^a may be formed of paper, cardboard, pressed paper or other suitable materials. The major portion of the disc 13^a may be domed as illustrated or may have any other desired shape. In accordance with this form of the invention the disc 13 has a down-turned or in-turned peripheral flange 32. The flange 32 is an integral part of the disc 13^a and is continuous or annular. When the flange 29 of the metal ring 15 has the configuration illustrated throughout the drawing, the peripheral corner of the disc 13^a where the flange 32 joins the body of the disc is engaged by the under side of the ring flange 29. This corner 33 of the disc 13^a may be

inclined or sloped to conform to the pitch of the flange 29 and if desired may be such that the upper surface of the disc 13^a is flush with the upper surface of the rim 30. The cooperation of the flange 29 with the corner 33 dependably holds the disc 13^a against outward movement and displacement and firmly maintains the disc in place. The outer surface of the flange 32 may cooperate with the inner surface of the ring part 28 and this engagement may hold the disc 13^a against lateral movement. The lower edge of the flange 32 rests on the upper side of the head 12. This engagement dependably holds the disc 13^a against inward movement. Thus it will be seen that the downwardly projecting flange 32 cooperates with the head 12 to hold the disc 13^a in the desired spaced relation to the head 12. The flange 32 is proportioned so that the corner 33 is engaged by the ring flange 29 when the lower edge of the flange 32 rests on the head 12. It is to be particularly noted that the construction illustrated in Figs. 6 and 8 of the drawing provides for the retention of the disc 13^a against inwardly as well as outward movement without the employment of a spacer.

Figs. 7 and 9 of the drawing illustrate a form of the invention wherein the head 12^a is shaped or provided with means for holding the disc 13 against inward movement. In this form of the invention the container body 10, the disc 13 and the seam ring 15 may be the same as illustrated in Figs. 1 to 4, inclusive, of the drawing.

The head 12^a, corresponding in function to the head 12, is shaped so that it has a part cooperating with the under side of the disc 13 adjacent its periphery. In practice this part of the head 12^a may be in the nature of a raised or embossed ridge. In the drawing I have illustrated the major portion of the head 12^a embossed or raised so that the disc 13 rests directly on it. The disc 13 has its peripheral portion held between the flange 29 and the head 12^a and is prevented from moving either inwardly or outwardly and the flange 29 serves to prevent lateral shifting of the disc. The embossing or raising of the major portion of the head 12^a, as just described, provides or leaves an annular groove 35 at the inner side of the flange 25. The inner part 28 of the metal ring 15 is received in this annular groove 35.

The present invention provides a container closure construction embodying an outer member or disc 13 or 13^a that is dependably retained in place in spaced relation to the body or head 12 of the closure without resorting to the use of padding, adhesive or a central support. It is to be particularly noted that the top closure does not have any exposed corners or edges. The rim 30 may lie substantially flush with the upper surface of the disc 13 or 13^a and joins the flange 29 at a rounded corner. The part 27 of the rim 30 is round and smooth where it engages about the edge of the rim 26. The flange 29 of the metal ring 15 has firm holding engagement with the peripheral portion of the disc 13 or 13^a to dependably hold the same against movement and loss.

Having described only typical preferred forms and applications of my invention, I do not wish to be limited or restrained to the specific details herein set forth, but wish to reserve to myself any variations or modifications that may appear to those skilled in the art or fall within the scope of the following claims:

Having described my invention, I claim:

1. A container comprising a container body, 7

and a closure for the body comprising a head, an axial flange on the head fitting in the body, a lateral rim on the flange engaging over an end of the body, a disc spaced axially outward from the head, a metal ring including an axial part engaged between said axial flange and the surface of the disc, an inwardly projecting radial flange on the upper end of said part holding the disc against axial outward movement, and an outwardly projecting lateral rim extending from the inwardly projecting flange and seamed onto the first mentioned rim, and an inturned axial flange on the disc engaging the head to hold the disc spaced from the head.

15 2. A container comprising a container body, and a closure for the body comprising a head, an axial flange on the head fitting in the body, a rim on the axial flange projecting outwardly beyond an end of the body, a disc overlying the head, and a metal seam ring including an axially extending part of larger diameter than the disc fitting between the periphery of the disc and the internal surface of the said axial flange, and an inwardly projecting flange on the said part cooperating with the peripheral portion of the disc to hold the disc against outward axial movement.

30 3. A container comprising a container body, and a closure for the body comprising a head, an axial flange on the head fitting in the body, a rim on the axial flange projecting outwardly beyond an end of the body, a disc overlying the head, and a metal seam ring including an axially extending part of larger diameter than the disc fitting between the periphery of the disc and the internal surface of the said axial flange, a flange at the outer end of said part overlying the peripheral portion of the disc to hold the disc against axial outward movement, and a rim connected with the last named flange and seamed onto the rim of the head.

45 4. A container comprising a container body, and a closure for the body comprising a head, an axial flange on the head fitting in the body, a rim on the axial flange projecting outwardly beyond an end of the body, a disc overlying the

head, a metal seam ring including an axially extending part fitting between the internal surface of the said axial flange and the circumferential surface of the disc to surround the disc and hold it against lateral movement, an inwardly projecting flange on said part overlying the upper surface of the disc to hold the disc against upward movement, and a laterally projecting rim extending from the inwardly projecting flange and seamed on the rim of the head, and means holding the disc spaced from the head.

5 5. A container comprising a container body, and a closure for the body comprising a head, an axial flange on the head fitting in the body, a rim on the axial flange projecting outwardly beyond an end of the body, a disc overlying the head, a spacer spacing the disc from the head, and a metal seam ring including an axially extending part engaged between the internal surface of the said axial flange and the circumferential surface of the disc, an inwardly projecting flange on the axial part overlying the disc adjacent its periphery to hold the disc against upward movement, and an outwardly projecting lateral rim joined with the last named flange extending outwardly over and seamed to the rim of the head.

15 6. A container comprising a container body, and a closure for the body comprising a head, an axial flange on the head fitting in the body, a rim on the axial flange projecting outwardly beyond an end of the body, a disc overlying the head, means holding the disc spaced above the head, and a metal seam ring comprising an axial part engaged between the internal surface of said axial flange and the circumference of the disc to hold the disc against lateral movement, an inwardly projecting lateral flange on the upper end of said axial part engaging the upper peripheral corner portion of the disc to hold the disc against upward movement, and an outwardly projecting lateral rim extending from the last named rim to engage over the first named rim and wrapped about its peripheral edge.

MAXIMILIAN P. LINK. 45
